UNITED STATES PATENT OFFICE.

WALDEN T. ROWELL, OF CHICAGO, ILLINOIS, ASSIGNOR OF ONE-HALF TO C. P. HARRIGAN, OF CHICAGO, ILLINOIS.

TIME-SWITCH FOR ELECTRIC LIGHTS.

1,294,540.

Specification of Letters Patent. Patented Feb. 18, 1919.

Application filed May 11, 1918. Serial No. 233,943.

To all whom it may concern:

Be it known that I, WALDEN T. ROWELL, a citizen of the United States, residing at Chicago, in the county of Cook and State 5 of Illinois, have invented certain new and useful Improvements in Time-Switches for Electric Lights, of which the following is a specification.

The time switch of the present invention 10 is designed as a more perfect embodiment of the principle set forth in Patent No. 1,194,078, issued to me August 8, 1916.

The object of the present invention is to 15 so construct and arrange the mechanism for performing the several operations in question that it will be neat and compact in form, certain of its operation, and conformable in certain of its features to standard constructions employed in the clock making 20 art. The invention is designed for use in connection with an electric lighting switch of the pull variety which requires a pull and release of the chain or cord to move the switch, either to the on or off position. The 25 invention is directed to the means provided for certainly maintaining the clock mechanism in wound position by connecting the winding arbor with the switch mechanism in such a way that the arbor will be moved 30 with the setting mechanism whenever the spring shall have unwound to a predetermined degree, thereby insuring a proper winding of the mechanism with each setting 35 of the switch irrespective of the time period for which the switch is adjusted.

The invention is primarily intended for 40 use in apartment buildings, stores, or display windows, where it is desired to maintain the lights for a predetermined time without the supervision of an attendant, and to automatically and certainly extinguish 45 the lights after a lapse of time.

A further object of the invention is to 45 provide means independent of the automatic means for lighting or switching off the lights as occasion may require; to provide means for insuring a starting of the clock mechanism after the mechanism has been set, and to improve the general construction, 50 arrangement, and mounting of the device as a whole, so that it may be housed within a comparatively small compass and located in the basement, switch box, or other inconspicuous place.

In the drawings:

Figure 1 is a side elevation of the entire device showing the same in the set or on position, and showing the details of the tripping mechanism;

Fig. 2 is a similar view in the same position showing the mechanism in released position;

Fig. 3 is a view of the opposite side of the mechanism showing the winding features;

Fig. 4 is an end elevation skeletonized by the removal of the clock train; and

Fig. 5 is an inside view of the side plate which supports the tripping mechanism.

The mechanism as a whole is mounted 70 upon and carried by a bracket 6 secured to a wall 7 or other convenient support, which bracket supports a base plate 8 to which is secured an upstanding side plate 9 which affords connection for the tripping mechanism presently to be described. The base plate also serves as a support for a pull switch 10 of the well known variety in common use at the present time of the general 75 type shown in the Hubbell Patent No. 649,308, which switch controls an electric circuit through the wires 11 leading to one or more incandescent lights 12 which may obviously be arranged and located in such suitable and convenient positions as the 80 lighting system for the building may require.

The pull switch is operated by means of a chain or cord 13, which, as best shown 85 in Fig. 5, connects with the upper arm 14 of a bell crank lever, the lower arm 15 of which carries an outwardly extending pin 16 which passes through a vertically elongated slot 17 near the lower outer corner of the side plate 9. The bell crank 14 is 90 mounted upon a pivot stud 18 inwardly extending from the side plate at a point slightly inside of the slot 17.

The bell crank lever can be operated by 95 hand through the medium of a depending chain or cord 19 which serves to exert a pull on the short end of the bell crank lever which serves to draw forward the lower arm of the lever, and thereby draw forward the switch chain 13 which will serve to operate 100 the switch, either on or off, independently of the automatic mechanism, the pin 16 in these circumstances riding idly within the slot 17.

without interference from the automatic mechanism.

The pin 16 coöperates with an elongated slide plate 20 which is provided with two elongated slots 21 and 22 respectively, through which are entered guide pins 23 and 24 respectively, the arrangement being one which affords to the slide plate a straight line movement across the outer face 10 of the plate 9. The slide plate is provided on its under edge near its outer end with a cam projection 25 which bears upon the underlying pin 16, so that, as the slide plate is drawn back from the set position shown 15 in Fig. 1 to the tripped position shown in Fig. 2, it will cause the pin 16 to be forced down and then released as the medial or apex point of the cam projection passes the pin, with the result that the bell crank lever will be rocked forward and then released, thereby imparting a corresponding pull and release to the switch chain 13. The retraction of the slide plate is effected by the pull of a pair of coil springs 26, the 20 forward ends of which are hooked through a flange 27 at the outer end of the slide plate, and the rear ends of which are hooked through a flange 28 formed on an upstanding arm 29 which is secured to the edge of 25 the base plate near the rear side thereof. The center or unslotted portion of the slide plate is provided with an upstanding projection 30, which carries a pin 31 which is entered through an elongated slot 32 in 30 a latch lever 33 rigidly secured to the outer end of a setting shaft 34, which latter is journaled through the side plate 9 and extends beneath the clock train and through a pair of supporting lugs 35 which project 35 upwardly from the base plate 8, as shown in Fig. 4. The opposite end of the shaft carries a rigidly mounted finger 36 which affords the means whereby the shaft is turned concurrently with the winding of the 40 mechanism by means to be presently explained. A coil spring 38 encircles a boss 39 on the end of the setting shaft 34, the in-turned end 37 of the spring engaging the heel 40 of a main operating lever 41 which 45 is loosely mounted on the setting shaft 34, the arrangement being one whereby the lever will return freely, under spring tension, upon its release, without moving the shaft 34. When the lever is engaged with the 50 shaft, a continued movement of the lever will cause a turning movement of the setting shaft through an angle of about forty-five degrees. This rocking of the shaft will be sufficient to move the latch lever 33 from 55 the released vertical position shown in Fig. 2 into the latched position shown in Fig. 1. In the latter position, the tip end 42 of the latch lever will ride under the outer end of a trip lever 43 loosely mounted upon a pivot 60 stud 44, which carries a coil spring 45 bear-

ing down on the inner end 46 of the trip lever. The inner end of the trip lever is provided with a hooked over finger 47 which, when the parts are set as in Fig. 1, will ride upon the edge 48 of a disk 49, 70 which disk carries an adjusting finger 50 held by spring tension into contact with an adjustable stop pin 51 which may be positioned within any one of a series of radially arranged stop holes 52 spaced in proper relation to represent hours of time in the movement of the clock mechanism. 75

The disk 49 is rotatably mounted on a pivot stud 53 carried by a vertically disposed slide plate 54 which abuts against the inner face of the side plate 9. The slide plate is provided with a guide slot 55 which embraces the hour hand arbor 56 of the clock mechanism and is provided at its lower end with an in-cut slot 59 which embraces 85 a guide pin 58, the arrangement being one which affords to the slide plate a slight degree of vertical movement which is required for the purpose of entraining the adjusting finger 50 with the hour hand pinion of the 90 clock mechanism in a manner to be now described. 95

The lower end of the slide plate 54 bears against the upper surface of the setting shaft 34 which, at the point of contact on 100 one of its sides, is flattened as at 60, so that, as the setting shaft is rocked in the operation of the latch lever, the flattened side 60 of the setting shaft will be brought into register with the lower end of the slide plate 105 54, allowing the latter to drop down sufficiently to entrain the spur pinion 61 with the hour pinion 62 on the end of the hour arbor 56. The spur pinion 61 lies in facial contact with and is secured to the disk 49 110 which carries the adjusting arm 50, so that these parts, when in train, will have movement commensurate with the hour hand movement of the clock, whereby, during the lapse of one hour, the adjusting arm 53 115 will have a counter-clockwise movement away from the adjusting pin 51 commensurate with one hour in the timed relation of the parts. 120

The disk 49, immediately adjacent to the 115 adjusting finger 50, is provided with a notch or recess 63 in which the finger 47 will fall as soon as the adjusting finger 50 has returned to normal or released position designated X in Fig. 1. This dropping down of 120 the hooked-over finger 47 on the inner arm of the trip lever 43 imparts a slight lifting movement to the outer or engaging end of the trip lever, which, in turn, releases the tip end 42 of the latch 33 which allows the 125 latter to fly back to the normal vertical position under the pull of the spring 26 which operates through the medium of the pin 31 on the slotted slide bar 20. This movement of the slide bar causes the apex 130

of the cam 25 to ride over the pin 16 forcing down the latter and moving and releasing the bell crank lever 14 with a corresponding pull and release of the switch 5 chain 13.

For purposes of convenience, the spaced relation between the normal or release point and the first adjusting hole 52 of the series represents a period of an hour and a half, 10 and every space thereafter represents an additional hour, so that, if the stop pin 51 is set in the first position, it will require an hour and a half for the adjusting finger 50 to return to normal or releasing position, 15 and an additional hour for each sequential setting of the stop pin. It will be understood that the arm 50 with the disk 49 and the pinion 61 are under constant spring tension which tends to move these parts in a 20 clockwise direction, so that, until the parts are in train with the hour pinion and the return movement is begun, the adjusting arm 50 will lie in spring contact against the stop pin 51 irrespective of the position occupied 25 by the latter; and this contacting of the arm and stop will automatically take place every time the parts are released and the light is switched off. In this way the parts will be maintained in position to move 30 through a predetermined period as soon as the entraining is again effected by the latching of the latch lever in the operation of switching on the lights.

In order to lift the finger 47 out of the 35 notch 63 after the adjusting finger 50 has returned to the X-position, the latch lever 33 is provided near its tip end with an in-turned flange 64, as best shown in Fig. 4, which, when the parts are returned to released position, will ride under the inner end 40 of the trip lever 46 and raise the same sufficiently to lift the finger 47 above the level of the notch, thereby releasing the disk 48 and adjusting finger 50, and allowing the 45 latter to fly down until it contacts with the stop pin 51 which regulates the time for its return movement.

The clock mechanism is carried within a frame consisting of inner and outer side 50 plates 65 and 66 which are held in spaced relation by spacer pins 67 passing through the corners; and the clockwork carries the usual train of gear arbors of which only the arbor 56 for the hour hand is shown. The 55 spring 68 is mounted upon a spring shaft 69 which likewise carries a pinion 70 in mesh with a segmental rack 71 loosely mounted on the setting shaft 34. The segment is provided to wind up the spring by 60 the action of the lever 41 whenever it happens that the spring has unwound to a degree which makes the winding necessary. The movement of the lever 41 is imparted to the segment 71 through the medium of 65 a lever arm 72 which is connected with the

lever 41 at its pivotal center and extends in substantially right-angles relation thereto and moves therewith.

The lever arm 72 near its outer end has pivoted thereto a pawl 73 having a foot 74 70 which, when the lever 41 is returned to its rearmost position by the pull of the coil spring 38, bears upon the rearwardly extending portion of the rear end of the base plate 8 and holds the upper end of the pawl 75 thrust forward in the position shown in Fig. 3. The pawl is shouldered at the point 74^a to provide at its upper end a notched head 75 which, with the parts shown in the adjustment indicated in Fig. 3, lies in proper 80 relation to engage a stud 76 on the segment 71, so that, with the parts in this relation, when the lever 41 is pulled forward, the segment will be moved with the lever and act to wind up the spring during the operation of setting the trip mechanism; and with the notched head of the pawl thus engaged the corner 74^b of the pawl will lie in the plane of the finger 36 so that a continued 85 forward movement will bring the corner 74^b into contact with the finger, and a movement of the lever will both wind the spring and set the latch. The pawl is subject to the action of a flat spring 77 which tends to throw the notched member upward when the foot 74 is released from contact with the plate 8, so that unless the notched member is in engagement with the stud 76 at the 90 beginning of the lever stroke the pawl will be thrown back by the action of the flat 100 spring 77, allowing the notched end to clear the stud 76 and later the finger 36. This allows the lever 41 to swing forward idly without imparting any movement to the operating mechanism. In this way the mechanism can be wound and set only when the segment 71, being in train with the spring arbor, has, after a calculated period of time, 105 returned to the position shown in Fig. 3, which illustrates a position indicating a 11 nearly complete unwinding of the spring mechanism, that is, a position in which a rewinding of the mechanism will be necessary to insure a further operation of the device for any considerable period of time. 115

In view of the fact that the clock mechanism is held in stationary position, so that it is impossible to shake or jar the mechanism after winding, to insure a starting of the mechanism after it is wound up, the following devices are provided: The side frame 66 of the clock mechanism has pivoted thereto an arm 78 which carries an inwardly projecting coil spring finger 79 so disposed that when the arm is rocked rearwardly, the 120 spring finger will frictionally engage with the rim of the escapement wheel 80 of the clock mechanism and turn the same backward against the tension of the hair spring 81. This rocking movement is effected 125 130

through the contact of a stop pin 82 shown in dotted lines in Fig. 3, which projects inwardly from the inner face of the segment 71 and in position to engage a spring detent 5 83, which is pivoted concentrically with the lever arm 78 and bears against a stop 84 on the lower end of the lever arm 78, so that a forward movement of the spring detent will cause a rearward rocking of the lever arm 10 as the stop pin 82 engages the detent. On the return movement of the pin 82, it will lift the spring detent without imparting movement to the lever arm.

By means of this arrangement, as the segment 15 is advanced during the winding operation, the escapement wheel will be put under spring tension until the stop pin 82 has moved to a point where it will release the detent, at which time the coil spring 85 20 will act to suddenly return the lever arm to normal position, thereby imparting a sudden rotative movement to the escapement wheel which serves to set the clock train in motion.

25 The various operations will be generally understood from the foregoing description, but the same may be briefly summarized as follows: With the lights extinguished, the adjusting stop pin 51 will be set into a hole 30 corresponding to the periods of time during which it is desired to maintain the lights in the building. The main operating lever 41 will then be pulled forward and through engagement with the notched head of the 35 pawl 73 with the pin 76 on the winding segment will impart a winding movement of the spring arbor, which movement simultaneously results in an initiatory movement of the escapement wheel. After the parts thus 40 engaged have been slightly moved, the pawl will come into contact with the finger 36, and a continued forward movement thereafter will impart a partial rotation to the setting shaft 34. This rotative movement 45 of the shaft will bring the flat side thereof beneath the lower end of the slide plate 54, which will allow the latter to drop and entrain the pinion 61 with the hour pinion of the clock mechanism, so that the anti-clockwise movement of the adjusting finger will 50 begin.

Rotation of the setting shaft will also simultaneously rock back the latch lever 33 until its upper end passes under and engages with the trip lever 43, and the same movement of the latch lever will retract the slide plate 20 and cause the cam 25 to first bear down and afterward release the pin 16 which controls the pull and release movements of the switch chain. It will thus be seen that with a single operation of the hand lever, the clock mechanism will be wound, the trip mechanism set, the lights turned on, and the trip release mechanism 65 thrown into mesh with the clock train. The

lights will then remain burning until the trip release mechanism has been rotated to a degree required to bring the notch 63 beneath the finger 47 on the trip lever, at which time the finger will drop down, the latch will be tripped, and the springs 26 will throw back the slide plate, and thereby actuate the pin 16 to turn off the switch and extinguish the lights.

70 The mechanism is one which conforms perfectly to the standard requirements of the clock-makers' art, and permits the special mechanism described to be employed in association with clock-work of the usual design and without any modifications whatever in the structure of the clock mechanism. The device is certain in its operation, in that it eliminates the necessity for attending to the winding mechanism, so that no difficulty will be experienced by reason of 80 the fact that the clock is insufficiently wound to operate during the entire period for which the trip mechanism is adjusted.

75 The winding and setting movements both being dependent upon the engagement of the pawl with the segment, it necessarily follows that it will be impossible to set the trip mechanism until the motor mechanism has unwound to the degree necessary to secure this engagement. Thus, after the lights are 85 extinguished for the night at the selected hour, the mechanism will of necessity run idly for a predetermined period of time so that it will be impossible to switch on the light, save by the secondary or non-automatic hand mechanism, until the proper hour has arrived for the turning on of the lights in the evening. This will prevent the janitor or attendant from shirking his duty by turning on the lights at an earlier hour 90 than the one for which the adjustment is made, since the mechanism can be located in a locked housing which will prevent tampering with the adjustments. At the same time the arrangement is one which insures a 100 complete winding of the spring motor with each setting of the trip mechanism, so that ample power will always be stored up for maintaining the operation during the longest period of time for which the lights may 110 be kept burning. It will thus be seen that 115

not only does the mechanism provide suitable means for determining the period of illumination, but also provides adequate means for timing the illumination to begin 120 only at a predetermined hour, which is important in the practical operation of a device of this character.

125 Although in the normal and usual operation of the device, the lights will be turned on by the pull of the hand lever, and turned off by the trip mechanism, nevertheless, these on and off movements can be reversed by a pull and release of the secondary switch chain, so that the lights will be automati- 130

cally turned on when the mechanism is tripped, and can afterward be extinguished by a second pull of the secondary switch chain. This adjustment will be of advantage 5 in cases where the owner of a home may wish to leave the house vacant during the evening, with the assurance that the lights will be automatically turned on at a given hour to guard against intrusion before the 10 return of the owner. In the claims, therefore, where reference is made to the turning on and off of the several mechanisms, it will be understood that this language is intended as well to cover a reversal of these 15 operations.

I claim:

1. In a time controlled switch mechanism, the combination of a switch, mechanism for moving the switch to on and off positions, 20 hand-operated means for actuating the switch moving mechanism to turn on the switch, trip elements adapted to be set by the movement of the hand-operated means, one of the trip elements being in operative 25 relation with the switch moving mechanism, time controlled means for releasing the trip elements after a predetermined lapse of time, the release of said trip elements resulting in a turning off movement of the switch moving mechanism, a spring motor, and connections between the hand-operated means and the spring motor adapted to engage only when the motor is unwound to a predetermined extent for winding the motor with 30 the setting movement of the hand-operated 35 means, substantially as described.

2. In a time controlled switch mechanism, the combination of a switch, mechanism for moving the switch to on and off positions, 40 hand-operated means for actuating the switch moving mechanism to turn on the switch, trip elements adapted to be set by the movement of the hand-operated means, one of the trip elements being in operative 45 relation with the switch moving mechanism, time controlled means for releasing the trip elements after a predetermined lapse of time, the release of said trip elements resulting in a turning off movement of 50 the switch moving mechanism, a spring motor, a segment in train with the spring motor, and connections between the hand-operated means and the segment adapted to engage only when the motor is unwound to a 55 predetermined extent for winding the motor with the setting movement of the hand-operated means, substantially as described.

3. In a time controlled switch mechanism, the combination of a switch, mechanism for moving the switch to on and off positions, 60 hand-operated means for actuating the switch moving mechanism to turn on the switch, trip elements adapted to be set by the movement of the hand-operated means, one of the trip elements being in operative 65

relation with the switch moving mechanism, time controlled means for releasing the trip elements after a predetermined lapse of time, the release of said trip elements resulting in a turning off movement of the switch moving 70 mechanism, a spring motor, a segment in train with the spring motor, a pawl connected and movable with the hand-operated means, and a stop for holding the pawl in position to engage the segment only when the spring is unwound to a predetermined extent, the pawl maintaining engagement with the hand-operated means for winding the motor during the setting movement of the hand-operated means, substantially as 75 described.

4. In a time controlled switch mechanism, the combination of a switch, mechanism for moving the switch to on and off positions, 80 hand-operated means for actuating the switch moving mechanism to turn on the switch, trip elements adapted to be set by the movement of the hand-operated means, one of the trip elements being in operative 85 relation with the switch moving mechanism, time controlled means for releasing the trip elements after a predetermined lapse of time, the release of said trip elements resulting in a turning off movement of the switch moving mechanism, a spring motor, connections between the hand-operated means and the spring motor for winding the motor with the setting movement of the hand-operated 90 means, and a member movable with said connections for imparting a starting movement to the spring motor coincidently with the winding thereof, substantially as described.

5. In a time controlled switch mechanism, the combination of a switch, mechanism for moving the switch to on and off positions, 95 hand-operated means for actuating the switch moving mechanism to turn on the switch, trip elements adapted to be set by the movement of the hand-operated means, one of the trip elements being in operative 100 relation with the switch moving mechanism, time controlled means for releasing the trip elements after a predetermined lapse of time, the release of said trip elements resulting in a turning off movement of the switch moving mechanism, a spring motor, a segment in train with the spring motor, connections between the hand-operated means and the segment for winding the motor with the setting movement of the hand-operated means, and a member moved by said segment and adapted to impart a starting movement to the motor coincidently with the winding thereof, substantially as described.

6. In a time controlled switch mechanism, the combination of a switch, mechanism for moving the switch to on and off positions, 110 hand-operated means for actuating the switch moving mechanism to turn on the switch, trip elements adapted to be set by the movement of the hand-operated means, one of the trip elements being in operative 115 relation with the switch moving mechanism, time controlled means for releasing the trip elements after a predetermined lapse of time, the release of said trip elements resulting in a turning off movement of the switch moving mechanism, a spring motor, a segment in train with the spring motor, connections between the hand-operated means and the segment for winding the motor with the setting movement of the hand-operated means, and a member moved by said segment and adapted to impart a starting movement to the motor coincidently with the winding thereof, substantially as described.

120

125

130

- movement of the hand-operated means, one of the trip elements being in operative relation with the switch moving mechanism, time controlled means for releasing the trip elements after a predetermined lapse of time, the release of said trip elements resulting in a turning off movement of the switch moving mechanism, a spring motor, a segment in train with the spring motor, connections between the hand-operated means and the segment for winding the motor with the setting movement of the hand-operated means, and a spring finger moved by said segment adapted to impart a starting movement to the motor coincidently with the winding thereof, substantially as described.
7. In a time controlled switch mechanism, the combination of a switch, a draw connection for operating the switch to on and off position by a pull and release movement for each switch operation, a pivotally mounted lever to one arm of which said draw connection is attached, a cam element acting upon the other arm of the lever for moving and releasing said arm with each passage of the cam element, hand-operated means for moving the cam element in one direction to turn on the switch, a latch moving with the setting movement of the hand-operated means, a tripping device for holding the latch and cam element against return movement, a spring motor, and time controlled means adapted to entrain with the spring motor for throwing the trip to release the latch after a predetermined period of time, substantially as described.
8. In a time controlled switch mechanism, the combination of a switch, a draw connection for operating the switch to on and off position by a pull and release movement for each switch operation, a pivotally mounted lever to one arm of which said draw connection is attached, a cam element acting upon the other arm of the lever for moving and releasing said arm with each passage of the cam element, hand-operated means for moving the cam element in one direction to turn on the switch, a latch movable with the setting movement of the hand-operated means, a tripping device for holding the latch and cam element against return movement, a spring motor, time controlled means adapted to entrain with the spring motor for throwing the trip to release the latch after a predetermined period of time, and means movable with the hand-operated means for entraining the time controlled means with the spring motor during the setting of the latch mechanism, substantially as described.
- 40 9. In a time controlled switch mechanism, the combination of a switch, a draw connection for operating the switch to on and off position by a pull and release movement for each switch operation, a pivotally mounted lever to one arm of which said draw connection is attached, a cam element acting upon the other arm of the lever for moving and releasing said arm with each passage of the cam element, hand-operated means for moving the cam element in one direction to turn on the switch, a latch movable with the setting movement of the hand-operated means, a tripping device for holding the latch and cam element against return movement, a spring motor, time controlled means adapted to entrain with the spring motor for throwing the trip to release the latch after a predetermined period of time, and means movable with the hand-operated means for entraining the time controlled means with the spring motor during the setting of the latch mechanism, substantially as described.
- 45 10. In a time controlled switch mechanism, the combination of a switch, a draw connection for turning the switch to on and off positions by a pull and release movement for each switch operation, a lever connected with said draw connection, hand-operated means for moving said lever to turn the switch to on position, a spring motor, time controlled means adapted to entrain with the spring motor for effecting a movement of the lever to turn the switch to off position after a predetermined period of time, and secondary means connected with the lever for operating the same independently of the operation of the time-controlled means, substantially as described.
- 50 11. In a time controlled switch mechanism, the combination of a switch, a draw connection for turning the switch to on and off positions by a pull and release movement for each switch operation, a lever connected with said draw connection, hand-operated means for moving said lever to turn the switch to on position, a spring motor, time controlled means adapted to entrain with the spring motor for effecting a movement of the lever to turn the switch to off position after a predetermined period of time, and secondary means connected with the lever for operating the same independently of the operation of the time-controlled means, substantially as described.
- 55 12. In a time controlled switch mechanism, the combination of a switch, a draw connection for turning the switch to on and off positions by a pull and release movement for each switch operation, a lever connected with said draw connection, a setting shaft, hand-operated means for turning the setting shaft, a latch member carried by the setting shaft, a cam element having operative connection with the latch member and movable conformably therewith, the cam element acting to impart a pull and return stroke to the lever with the setting movement of the setting shaft, a spring for returning the cam

lever to one arm of which said draw connection is attached, a cam element acting upon the other arm of the lever for moving and releasing said arm with each passage of the cam element, hand-operated means for moving the cam element in one direction to turn on the switch, a latch movable with the setting movement of the hand-operated means, a tripping device for holding the latch and cam element against return movement, a spring motor, time controlled means adapted to entrain with the spring motor for throwing the trip to release the latch after a predetermined period of time, and means movable with the hand-operated means for entraining the time controlled means with the spring motor during the setting of the latch mechanism and adapted to disentrain the parts with the releasing of the latch mechanism, substantially as described.

60 13. In a time controlled switch mechanism, the combination of a switch, a draw connection for the switch adapted to operate the switch to on and off positions by a pull and release movement for each switch operation, hand-operated means for turning the switch to on position, a spring motor, time controlled tripping mechanism adapted to entrain with the spring motor and effect a turning off of the switch after a predetermined period of time, and secondary hand-controlled means for operating the switch independently of the operation of the time controlled mechanism, substantially as described.

65 14. In a time controlled switch mechanism, the combination of a switch, a draw connection for turning the switch to on and off positions by a pull and release movement for each switch operation, a lever connected with said draw connection, hand-operated means for moving said lever to turn the switch to off position after a predetermined period of time, and secondary means connected with the lever for operating the same independently of the operation of the time-controlled means, substantially as described.

70 15. In a time controlled switch mechanism, the combination of a switch, a draw connection for turning the switch to on and off positions by a pull and release movement for each switch operation, a lever connected with said draw connection, a setting shaft, hand-operated means for turning the setting shaft, a latch member carried by the setting shaft, a cam element having operative connection with the latch member and movable conformably therewith, the cam element acting to impart a pull and return stroke to the lever with the setting movement of the setting shaft, a spring for returning the cam

- element to retracted position, a trip for holding the latch in set position, a spring motor, and connections between the spring motor and trip member for operating the trip to release the latch after a predetermined period of time and permit a return movement of the cam and an operating movement of the lever controlling the switch, substantially as described.
13. In a time controlled switch mechanism, the combination of a switch, a draw connection for turning the switch to on and off positions by a pull and release movement for each switch operation, a lever connected with said draw connection, a setting shaft, hand-operated means for partially rotating the shaft, a latch member carried by the shaft, a slide plate having operative connection with the latch member, a cam on the slide plate, an operative connection between the cam and the draw lever for imparting a pull and release movement to the latter with each passage of the cam, a spring for returning the draw bar to normal position when the latch is released, a trip for holding the latch in set position, a spring motor, and time controlled means for actuating the tripping mechanism to release the latch after a predetermined period of time, substantially as described.
14. In a time controlled switch mechanism, the combination of a switch, a draw connection for turning the switch to on and off positions by a pull and release movement for each switch operation, a lever connected with said draw connection, a setting shaft, hand-operated means for partially rotating the shaft, a latch member carried by the shaft, a slide plate having operative connection with the latch member, a cam on the slide plate, an operative connection between the cam and the draw lever for imparting a pull and release movement to the latter with each passage of the cam, a spring for returning the draw bar to normal position when the latch is released, a trip for holding the latch in set position, a spring motor, an adjusting finger, the adjusting finger and trip being correlated to move the trip to releasing position after the return movement of the adjusting finger has been completed, and an element connected with the adjusting finger and adapted to entrain with the spring motor for timing the return movement of the adjusting finger, substantially as described.
15. In a time controlled switch mechanism, the combination of a switch, a draw connection for turning the switch to on and off positions by a pull and release movement for each switch operation, a lever connected with said draw connection, a setting shaft, hand-operated means for partially rotating the shaft, a latch member carried by the shaft, a slide plate having operative connection with the latch member, a cam on the slide plate, an operative connection between the cam and the draw lever for imparting a pull and release movement to the latter with each passage of the cam, a spring for returning the draw bar to normal position when the latch is released, a trip for holding the latch in set position, a spring motor, and time controlled means for actuating the tripping mechanism to release the latch after a predetermined period of time, substantially as described.
16. In a time-controlled switch mechanism, the combination of a switch, a connection for turning the switch to on and off positions, a spring motor provided with winding mechanism, hand operated means adapted to engage with the winding mechanism only when the spring motor is unwound to a predetermined extent, time-controlled tripping mechanism adapted to entrain with the spring motor and effect a turning off of the switch after a predetermined period of time, and connections between the hand operating means and the tripping mechanism adapted to engage only when the hand operated means are in engagement with the winding mechanism for setting the tripping mechanism concurrently with the winding of the spring motor, substantially as described.
17. In a time-controlled switch mechanism, the combination of a switch, means for moving the switch to on and off positions, a spring motor, gearing in train with the spring motor for winding the same, a hand operated lever provided with a contact device for engaging the winding gearing only when the spring motor is unwound to a predetermined extent, tripping mechanism adapted to entrain with the spring motor for turning off the switch after a predetermined period of time, and a connection for setting the tripping mechanism operable by contact with the contact device only when the latter is in operative engagement with the winding gearing, whereby the movement of the hand operated lever will concurrently wind the motor and said tripping mechanism, substantially as described.
18. In a time-controlled switch mechanism, the combination of a switch, means for moving the switch to on and off positions, a spring motor, winding gear elements in train with the spring motor, a hand operated lever mounted in operative relation

to one of the winding gear elements, a pawl carried by the hand lever, a stop on the last mentioned gear element adapted to engage the pawl only when the spring motor is un-
5 wound to a predetermined extent, tripping elements adapted to entrain with the spring motor and effect a turning off of the switch after a predetermined period of time, and

means for setting the trip elements adapted to be operatively engaged by the pawl only 10 when the latter is in operative engagement with the last mentioned winding gear element for concurrently winding and setting the mechanism by operation of the hand lever, substantially as described.

WALDEN T. ROWELL.
